UNITED STATES PATENT OFFICE

CECIL J. FERGUSON, OF SPOKANE, WASHINGTON, ASSIGNOR OF ONE-FOURTH TO
PASCULE L. CIVILE, OF SPOKANE, WASHINGTON

PASTE EJECTOR

Application filed May 31, 1929. Serial No. 367,430.

My invention relates to paste ejectors and is particularly adapted for use in ejecting tooth paste from collapsible tubes in its application to tooth brushes. Certain objects 5 of the invention are to provide a paste ejector comprising a casing or container for a collapsible tube and means whereby the paste is squeezed from the tube through a discharge nozzle and onto a brush. Further objects 10 are to provide rest and guide means whereby the brush is held and moved in proper position with respect to the nozzle, together with means for retaining the several elements of the device in their normally closed positions, 15 and other details of construction as more fully hereinafter set forth.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:

25 Figure 1 is a view in perspective showing the exterior of the device;

Fig. 2 is a view in vertical section taken substantially on a broken line 2, 2 of Fig. 1;

30 Fig. 3 is an enlarged view in vertical section of the discharge end portion of the device; and

Fig. 4 is a view in horizontal section taken substantially on a broken line 4, 4 of Fig. 1.

35 Referring to the drawings throughout which like reference numerals designate like parts, the numeral 5 indicates a casing which may have a plurality of holes 6 in its rear portion whereby the casing may be fastened 40 to a wall or the like. The bottom 7 of said casing may have flanges 8 projecting therefrom with holes 9 whereby the casing may be secured to a shelf or the like.

45 The casing 5 is provided with a door 10 hinged thereto and provided with springs 11 that are arranged to normally retain said door in a closed position. A discharge nozzle 12 projects from the bottom 7 of said casing and is provided with a rectangular orifice 13 with round corners so that the paste

will issue therefrom in the form of a ribbon as will be understood.

A swinging member 14 is hinged or otherwise pivoted at 15 to the bottom 7 of the casing. Said member is provided with a shoulder 16 which serves as a closure for the orifice 13 and a spring 17 is arranged to retain said member with its shoulder in the closed position. The remote end of said member is provided with a lip 18 for reasons 60 hereinafter specified.

Corresponding slots 19 are provided on the sides of the casing 5 and extend nearly the full height of the casing. A collapsible tube 20 has its neck either screwed into the interior end of the nozzle 12 as shown at 21 or is held therein by a set screw 22 as shown in Fig. 2.

A key 23 is slidably disposed in the slots 19 and is provided with shoulders 24 whereby 70 it is retained in said slots. Said key is provided with a longitudinal slot 25 which is slipped over the compressed upstanding end of the collapsible tube 20 and said key may be turned by an exterior handle 26 to force 75 the contents of the tube out through the nozzle as will be understood.

Referring to Fig. 3, in the use of my device and assuming that dental cream is used, a tooth brush 27 is placed against the swinging 80 member 14 with its outer end resting on the lip 18. Said member is slowly pushed from the full line to the dotted position with the tooth brush in one hand and with the other hand the key 23 is slightly turned at the 85 same time. In moving from the full to the dotted position the bristles of the brush will pass directly under the orifice 13 of the nozzle 12 and a ribbon of cream will be spread on said bristles as shown at 28.

90 It will now be apparent that I have provided a convenient means for applying paste to a brush. This means is at hand so that the paste is always available when needed and may be applied easily and quickly without the necessity of getting out and opening a tube, closing and putting it away as has heretofore been done.

95 Having thus described my invention, it being understood that minor changes may 100

be resorted to in its construction without departing from its scope and spirit, what I claim and desire to secure by Letters Patent of the United States is:

- 5 In a paste ejector, the combination with a casing having a discharge nozzle and adapted to support and retain a collapsible tube container in dispersive communication with the discharge nozzle, of a swinging member
- 10 for the nozzle end of the casing, a flat offset shoulder portion for the swinging member which is so formed and positioned as to have free sliding contact with the discharge nozzle, said shoulder portion forming a clo-
- 15 sure for the nozzle when in its normal position, a lip portion for the lower end of the swinging member, the swinging member being supported hingedly on the casing so that when actuated by a brush in contact with the
- 20 end lip of said member it is caused to swing in an arc bringing the brush directly under the unclosed nozzle for receiving a charge of paste therefrom.

In testimony whereof I affix my signature.

25 CECIL J. FERGUSON.
